FIREPROOF BUILDING CONSTRUCTION

John A. Ferguson, Pittsburgh, Pa., assignor of
one-third to Thomas E. Sturges, Pittsburgh,
Pa.

Application September 27, 1928
Serial No. 308,880

4 Claims. (Cl. 72—63)

My invention relates to fireproof building constructions, and more particularly to building structures of the type embodying structural metal supporting members and pre-formed slabs, tiles, 5 or the like, employed in conjunction with said members for constructing floors, roofs, and other enclosing units in building structures.

The present invention is primarily directed to a new and improved pre-formed or pre-cast unit, 10 slab, or tile, preferably made of hydraulic cement and sand and stone aggregates, reinforced to enable the units or slabs to carry superimposed loads and resist applied forces, according to engineering calculations and experience, and also 15 provided with interlocking load-supporting ends in the form of projecting and re-entrant portions arranged in predetermined order, so that when the slabs are laid in succession in the construction, the said portions fit into and engage with 20 each other in a manner to contribute to and materially increase the rigidity and stiffness of the construction.

My invention further contemplates providing the body of the slab, etc., with parallel reinforcing elements of such a character that the said 25 elements or portions thereof are utilized as bearing surfaces designed to have direct contact with the structural members, and provide adequate means for the bearing or support of the 30 slabs upon wide or narrow structural members and, at the same time, provide spaces between the supporting surfaces of the structural members and the slabs, which spaces may be employed for receiving pipes, wires, etc. therein.

35 In the preferred embodiment of my invention, the reinforcing elements project from the ends of the slab, and extend under a portion of the interlocking projections, and are arranged on the respective slabs in a manner to provide, when 40 the slabs are assembled on the structural members end to end and side to side and in close contact, pairs of parallel overlapping reinforcing elements so arranged that each element of a pair has a vertical side for such overlapping contact with the other element of the same pair.

In the accompanying drawing, which illustrates an application of my invention:

Fig. 1 is a top plan view of a slab or tile embodying my invention;

50 Fig. 2, an end view;

Fig. 3, a transverse sectional view taken on line III—III of Fig. 1;

Fig. 4, a plan view of a floor construction embodying my invention; and

Fig. 5, a perspective view of the said floor construction.

Referring to the drawing, 5 designates the body of a pre-formed slab, tile, or the like, made up of suitable incombustible and insulating materials. As illustrated and as preferred, the body 5 is provided at each of its load supporting ends with a plurality of aligned projecting portions 6 and complementary projections 7, the projecting portions 6 being considerably wider than the 60 projections 7. In addition to said projections, the ends of the slab are each formed with complementary re-entrant portions or recesses 8 located between the said projections.

Extending longitudinally of the slab and projecting from the under face of the body, I provide a plurality of reinforcing or strengthening elements in the form of projecting ribs 9. It will be noted that these reinforcing elements, at 70 the ends of the slab, project therefrom under a portion of each of the projections 6, and under the entire width of each of the projections 7, thus reinforcing the said projections and providing bearing surfaces for the slabs, said bearing surfaces being designed to make direct contact 75 with the structural supporting members of the building structure.

It will be further noted that the reinforcing elements are so spaced apart that the elements of successive units arrange themselves in pairs 80 at their bearing or supporting end, and that each element of a pair is provided with a surface at one of its sides for contact with a similar surface on one of the sides of the other element 85 of the same pair.

With my form of slab and its interlocking load-supporting ends and reinforcing elements, I am enabled to employ various shapes of structural supporting members, such as channel members or I-beams and other shapes having either narrow or wide floor supporting flanges. In the drawing, I have illustrated junior I-beams 90 10 for receiving and supporting the interlocked ends of adjacent slabs.

When the slabs are placed on members 10 in 100 end-to-end and side-to-side relation, as shown by Figs. 4 and 5, the adjacent and load-carrying projections and their reinforcing elements of each slab may extend the full width of the flange of member 10, and thus provide a very considerable bearing surface for the slabs. The reinforcing elements, as shown by the said figures, when the slabs are laid, extend past each other or overlap on the supporting members 10, and also 105 function to provide spaces 11 adapted to receive 110

pipes, conduits, and other necessary appurte-
nances of a building structure.

In assembling the slabs, tiles, or the like on
the supporting members 10, they may be laid on
5 said members with each alternate slab turned in
the opposite direction from its adjacent succeed-
ing slab. This method of positioning the slabs
is clearly shown by Fig. 4; and in this connec-
tion attention is called to the fact that adja-
10 cent to the side edges of the slabs, the slabs are
reinforced throughout their lengths by two lon-
gitudinally extending reinforcing elements 9. If
found desirable, the slabs, etc. may be assembled
in staggered relationship, so that the longitudinal
15 joints between adjacent tiles, laid side by side,
are broken.

I claim:

1. A building construction embodying a plural-
ity of spaced structural members, a plurality of
20 load-supporting slabs each comprising a body
formed with longitudinally extending reinforcing
elements and load-supporting ends having pro-
jecting and re-entrant portions, said reinforcing
elements constituting the bearing surfaces of the
25 slabs and resting directly upon the structural
members, said elements each having a side face

in contact with a corresponding face of another
slab.

2. A building slab comprising a body formed
with projecting and re-entrant portions at its
load-supporting ends and with integral longitudi-
nally extending reinforcing elements extending
80 under the body and said projecting portions, said
elements constituting the sole load-bearing sur-
faces of the slab.

3. A building slab comprising a body formed at
85 opposite load-supporting ends with aligned projec-
tions and with aligned recesses located between
the projections, said body also having integral
longitudinally extending reinforcing elements
90 constituting the sole load-bearing surfaces of the
slab.

4. A building slab comprising a body provided
with depending reinforcing elements, the ends of
the slab being load-supporting and having pro-
jecting and reentrant portions, said elements ex-
95 tends under adjacent projecting portions, and
said elements at a side thereof being adapted to
overlap and contact with corresponding elements
of an adjacent slab.
